(57) **CLAIM**

The ornamental design of a precast concrete support for a bridge, as shown and described.

DESCRIPTION

FIG. 1 is a perspective view of a precast concrete support for a bridge showing my new design;

FIG. 2 is a top view thereof;

FIG. 3 is a rear view thereof;

FIG. 4 is a front view thereof;

FIG. 5 is a side view thereof, the opposite side view being a mirror image; and,

FIG. 6 is a vertical section view thereof, taken on the line 6—6 of FIG. 3.
